UNITED STATES PATENT OFFICE

OTTO ROSENSTEIN, OF SAN FRANCISCO, CALIFORNIA, ASSIGNOR TO ILLINOIS PACIFIC GLASS CORPORATION, OF SAN FRANCISCO, CALIFORNIA, A CORPORATION OF CALIFORNIA

GLASS-TANK FURNACE

Application filed August 23, 1926. Serial No. 130,958.

This invention relates to glass tank furnaces and especially to an improved construction thereof. To those skilled in the art it is well known that a very high and destructive heat must be maintained in these furnaces. As a result of this high heat, the molten glass eats its way through the furnace wall blocks and particularly through the joints between the blocks, and the furnace walls must therefore be frequently rebuilt to remedy this defect. It is the object of this invention to so improve the construction of such a furnace as to avoid a very considerable amount of this destructive effect and thereby overcome the necessity of so frequently rebuilding the furnace walls.

In the accompanying drawing, I have illustrated one specific embodiment of my invention, but it will be understood that the invention can be otherwise embodied and that the drawing is not to be construed as defining or limiting the scope of the invention, the claims appended to the specification being relied upon for that purpose.

Referring to the figures of the drawing:

Fig. 1 is a fragmentary sectional view through a glass tank furnace embodying my invention.

Fig. 2 is a fragmentary elevation of one of the inner side walls thereof.

In the drawing, 1 indicates the bottom wall and 2 one side wall of the furnace. These walls are constructed of relatively large blocks 3 of heat-resisting clay. The greatest amount of deterioration of the side walls, as above referred to, takes place near the bottom and top of the furnace. This is particularly due to the pressure of the liquid bath being greatest at the bottom and the temperature thereof being greatest at the top. As has

also been illustrated, the main deterioration of the walls takes place at the horizontal joints between the blocks. In accordance with my invention, I so construct the side walls as to avoid locating any of these joints near these points of greatest destruction. As illustrated in the drawing, I form the bottom and side walls of relatively large blocks 3, but in constructing the side walls I use blocks 4 at the bottoms thereof which are of consid-

erably less thickness vertically than the vertical thickness of the bottom wall.

It may be stated that the wear on the bottom 1 of the furnace is such that from one-half inch to one inch of the upper side thereof deteriorates per year. The side wall joint 7 has ordinarily been placed on a level with this top surface and this construction has resulted in a very irregular wearing away of the bottom 1 and a fast deterioration of the side wall 60 at this joint. By the improved arrangement illustrated such rapid deterioration of the side wall is prevented and the bottom wall is permitted to wear down a considerable amount (to a position near the joint) before 65 replacement of the bottom wall becomes necessary.

The provision of this initial bottom layer of smaller blocks also brings the top surface of the next block 3 thereon to a position considerably above the bottom of the furnace. This arrangement furthermore so elevates the next large block thereabove that the upper surface of this top large block is above the normal top surface 5 of the molten bath 6. 75

The result of the construction above described is as follows:

The first horizontal joint 7 between the side wall blocks is considerably below the bottom wall of the furnace and is therefore not affected by the molten bath. The intermediate joint 8 is considerably above the bottom of the furnace and considerably below the normal top surface 5 of the molten bath. This joint 8 is therefore located intermediate these most destructive points and is therefore less affected by the deleterious effects of the molten bath than when located near the bottom and top in the ordinary furnace construction.

The location of the greatest destructive effect on the furnace walls is indicated by broken lines in Figure 1 of the drawing. In my improved construction, the blocks are so arranged that the greatest resistance to this destructive effect is located at these points. By the use of this improved construction, the furnace walls need not be replaced until the same have deteriorated to substantially the amount indicated by the broken lines.

It is believed that the construction and material advantages of my invention will be clear from the above description taken in connection with the accompanying drawing.

Having thus described my invention, what I claim and desire to secure by Letters Patent is—

1. A glass tank furnace of the character described having a bottom wall and side walls, said side walls comprising a lowermost row of bricks substantially less in vertical thickness than said bottom wall, a second row of bricks extending substantially above the top surface of said bottom wall and a third row of bricks extending to a point above the normal top surface of the molten bath contained by the furnace.

2. A glass tank furnace comprising a bottom wall and side walls formed of horizontally disposed rows of bricks, the lowermost row of bricks in said side walls being approximately one half the thickness of said bottom wall whereby the other bricks in the side walls may be repeatedly replaced without necessitating the disturbance of said lowermost row of bricks.

3. A glass tank furnace comprising a bottom wall and side walls formed of horizontally disposed rows of bricks, the lowermost row of bricks in said side walls being approximately one half the thickness of said bottom wall whereby the other bricks in the side walls may be repeatedly replaced without necessitating the disturbance of said lowermost row of bricks, and whereby erosion of said bottom wall will not expose said lowermost row of bricks to contact with the bath within the furnace until said bottom wall is worn to one half its original thickness.

OTTO ROSENSTEIN.
